GUNS HAVING MEANS FOR HORIZON-
ADJUSTMENTEduard Müller, Dusseldorf, Germany, assignor to
Rheinmetall-Borsig Aktiengesellschaft, Dussel-
dorf, GermanyApplication March 3, 1936, Serial No. 66,947
In Germany August 29, 1930

6 Claims. (Cl. 89—37)

This invention relates to gun mountings for use on unsteady platforms, ships and the like, and comprising an undercarriage pivotable about a vertical axis on a pedestal, and a cradle for elevation the trunnion axis of which can be horizontalized to adjust for tilting movement of the platform. For this purpose the gun may be made pivotable in the undercarriage about an axis disposed between the axis of training and the axis of elevation, said intermediate or horizontalizing axis being substantially at right angles to both the training axis and the elevation axis. In guns of this kind, when large movements of the support occur, the gun layers are subjected to great inconvenience. The telescopic sighting means associated with a system which is capable of horizontalizing adjustment perform angular deflections which are as large for those parts of the gun which are not moved during such adjustment as those of the support or pedestal itself in space. The gun layer who works from a stand or seat which does not move with the horizontalizing adjustment must follow such movement by uncomfortable and fatiguing movements of his head and body.

According to the invention, movements of the eye-piece members of the telescopic sighting means away from the gun layer are avoided. Two constructional arrangements embodying the invention are shown applied to one and the same gun in the accompanying drawing, in which

Fig. 1 is a side elevation, and

Fig. 2 a plan view of the described example.

In the gun shown in elevation in Fig. 1 and in plan in Fig. 2, the two gun barrels A, A₁ are mounted, by means of a common trunnion C which carries their recoil cradles B, B₁ so as to be pivotable vertically in a cross-shaped saddle D, which latter member is adapted to pivot about horizontalizing-adjustment pins E and rests in a lower gun carriage G which is adapted to turn about a vertical axis on the pedestal F.

The gun trainer's seat H and the training mechanism J are arranged at the rear between the two gun barrels on the lower carriage G which does not take part in the horizontalizing-adjustment movement. The sighting device K for training is attached to the pin E of the saddle D and moves with it during the horizontalizing-adjustment, its eyepiece K₁ being situated in the prolongation of the axis of the pin E and in front of the eye of the gun trainer.

The gun elevator's seat L, the sighting device M for elevation, and the elevating mechanism N

are fitted in front of the gun carriage between the two gun barrels, on the saddle D which moves during the horizontalizing adjustment, and takes part in such movement which is produced, for example, by means of a hand wheel O or by power driven mechanism.

It will be seen that the disclosure covers two different ways of achieving the object of the invention. In the first arrangement the sighting telescope is so mounted on the saddle pivotable about the horizontalizing axis that the optical axis of the eye-piece is co-axial with said axis, whereby although the telescope turns about said axis from the view point of the gun layer, it does not move away from that axis and his line of vision.

In the second arrangement the gun layer's seat or stand is carried by the saddle which performs the adjustment movement about the horizontalizing axis, whereby, when the saddle along with the sighting telescope shift, the said seat or stand takes part in the shift and the undesired countermovement between the telescope and the gun layer is eliminated.

The drawing shows both arrangements applied to a gun mounting for two parallel guns, having separate elevating and training mechanisms, but the arrangements are applicable to a mounting for one or a plurality of guns, and either or both arrangements can be used.

I claim:

1. A gun mounting for use on unsteady platforms, ships, and the like comprising an undercarriage capable of turning about a vertical axis for training adjustment, a saddle capable of horizontalizing turning movement in said undercarriage about a horizontal axis lying in the same vertical plane as said vertical axis, a gun cradle capable of elevational adjustment in said saddle, and sighting means including an eye-piece arranged on said horizontalizing saddle with the eye-piece substantially coaxial with the horizontalizing axis.

2. A gun mounting for use on unsteady platforms, ships, and the like comprising an undercarriage capable of turning about a vertical axis for training adjustment, a saddle capable of horizontalizing turning movement in said undercarriage about a horizontal axis lying in the same vertical plane as said vertical axis, a gun cradle capable of elevational adjustment in said saddle, sighting means on the horizontalizing saddle, and a gunner's seat carried by said saddle in convenient proximity to the sighting means.

3. A gun mounting for use on unsteady platforms, ships, and the like comprising an under-carriage capable of turning about a vertical axis for training adjustment, a saddle capable of horizontalizing turning movement in said under-carriage about a horizontal axis lying in the same vertical plane as said vertical axis, a gun cradle capable of elevational adjustment in said saddle, sighting means for training including an eye-piece arranged on said horizontalizing saddle with the eye-piece substantially coaxial with the horizontalizing axis, sighting means for elevation, and a gun elevator's seat, said last mentioned sighting means and seat being mounted on said saddle.

4. A gun mounting for use on unsteady platforms, ships, and the like comprising an under-carriage tiltable about an axis perpendicular to the platform, a saddle mounted in said under-carriage and capable of turning about a horizontalizing axis lying in the same vertical plane as the said perpendicular axis, and sighting means fixed on said saddle, said means having an eye

piece arranged co-axially with said horizontalizing axis.

5. A gun mounting for use on unsteady platforms, ships, and the like comprising an under-carriage tiltable about an axis perpendicular to the platform, a saddle mounted in said under-carriage and capable of turning about a horizontalizing axis lying in the same vertical plane as the said perpendicular axis, and sighting means including a gunner's seat attached to said saddle.

6. A gun mounting for use on unsteady platforms, ships, and the like comprising an under-carriage tiltable about an axis perpendicular to the platform, a saddle mounted in said under-carriage and capable of turning about a horizontal axis lying in the same vertical plane as the said perpendicular axis, sighting means for training adjustment fixed to said saddle, said sighting means having an eye-piece co-axial with said horizontalizing axis and sighting means for elevation adjustment fixed to said saddle and including a gunner's seat.
